UNITED STATES PATENT OFFICE.

OSCAR ANDERSON, OF CHELSEA, WISCONSIN.

LOCKING MEANS FOR BOXES.

1,146,230.

Specification of Letters Patent. Patented July 13, 1915.

Application filed June 17, 1914. Serial No. 845,717.

To all whom it may concern:

Be it known that I, OSCAR ANDERSON, a citizen of the United States, residing at Chelsea, in the county of Taylor and State 5 of Wisconsin, have invented certain new and useful Improvements in Locking Means for Boxes; and I do hereby declare the following to be a full, clear, and exact description of the invention, such as will 10 enable others skilled in the art to which it appertains to make and use the same.

This invention relates broadly to locking mechanism for boxes and has particular reference to devices of that character in 15 which the locking means consist mainly of manually operable sliding bolts concealed in the structure of the box so that only the initiated can operate the same in order to gain access to the contents.

As a principal object this invention contemplates the provision of a box which shall be unlocked only by the operation of some such secret mechanism as above described and which at the same time shall 25 present an outward appearance of the ordinary receptacle of this character.

The above and additional objects are accomplished by such means as are illustrated in the accompanying drawings, described 30 in the following specification and then more particularly pointed out in the claims which are appended hereto and form a part of this application.

With reference to the drawings, wherein 35 I have illustrated the preferred embodiment of my invention as it is reduced to practice, and throughout the several views of which like characters of reference designate similar parts, Figure 1 is a perspective view of a preferred form of this invention showing the same as it appears when locked, Fig. 2 is a similar view but showing the box as it appears when the bolts have been manipulated in order to unlock the same 45 and the lid thereof thrown back, Fig. 3 is a top plan view of the device, Fig. 4 is a transverse sectional view through the center of the device.

In taking up the description of the structural features of this invention reference 50 will first be had to Fig. 1 in which the device is most clearly shown as an entirety and in which the deceptive appearance of the locking means is emphasized. The box 55 and all the separate portions thereof are preferably formed of some hardened metal

which is not only calculated to resist all attacks made on the locking mechanism but is also capable of receiving a higher degree of finish in order to present an ornamental appearance. 60

The box is provided with the usual side walls 5, end walls 6 and bottom 7, which may be integral with each other or separately secured to form a whole which ever 65 may be deemed preferable. To the rear wall of the structure is pivotally secured the top 8 by means of the hinges 9, this top being provided with the integral depending flanges 10 which are adapted to closely fit 70 over the upper portion of the sides and end walls of the box in order to form a tight joint.

Slots 11 and 12 are formed in the cover 8 in the manner disclosed in Fig. 3, these slots 75 being of different sizes in order to accommodate various denominations of coins. These slots which permit coins to be dropped into the box are adapted to be covered or uncovered at will by the sliding 80 plates 13 which are pivoted to the top by means of the bolts 14 penetrating the cover 8 and the plates 13 from the under side of the former and threadingly received by suitable sockets in the ornamental knobs 15, the 85 latter also being adapted to receive the handle 16 by which the box may be carried about. These sliding plates are disposed as shown in Figs. 1 and 3 and have their meeting edges 17 disposed at an angle to 90 both the transverse and longitudinal axes of the box so that they are capable of being swung as shown in Fig. 3, one in each direction to reveal the slots 11 and 12 when it is desired to deposit coins in the box. 95

Turning now to the specific locking means that has been designed for use in connection with this box a suitable rounded molding 18 is provided on the two ends and the front of the box at a point immediately 100 below the flanges 10 when the cover has been lowered over the box. The two portions of molding secured to the front side of the box are spaced as shown at 19 and are provided with the longitudinal apertures 20 in which the locking bolt 21 is adapted to slide. The space thus left at 19 is adapted to be filled by the keeper 22 which is carried by the cover of the box and is provided with the integral boss 23 110 likewise longitudinally apertured so that when the cover is closed down upon the box

- an unbroken passage will be provided for the reception of the bolt 21. Immediately below the position occupied by the keeper 22 when the box is closed, is positioned the 5 false lock 24 provided with a key hole 25 in order to simulate an ordinary lock and thus lead astray the attention of those unacquainted with the real locking process of the coin receptacle.
- 10 The locking bolt 21 which as before stated is adapted to slide in the longitudinal passage formed by the molding 18 on the front side of the box and the keeper 23, is provided at its upper extremity with a raised 15 portion 26 and a rearwardly extending locking lug 27. The raised portion 26 is adapted to seat snug against the end of the molding 18 when the bolt is slid home in order to preserve the continuity of the surface 20 while the locking lug 27 is adapted to be received in a cutaway portion 28 formed in the adjacent extremity of the molding 18 which is affixed to the sides 6. Suitable 25 rounded outer coverings 29 having their meeting ends beveled as at 30 are adapted to be longitudinally slid on the molding 18 in order to cover every trace of the locking mechanism and it is only by first operating these coverings 29 that the box may 30 be unlocked.
- As shown in Figs. 2 and 4 of the accompanying drawings I have provided a tray 31 having side and end flanges 32 which is adapted to be received by the box in the 35 manner shown. If desired a transverse partition 34 may be provided to subdivide the tray into compartments and this partition may have connected thereto a handle 35 or other suitable means for the ready 40 removal of the tray from the receptacle. It will be noted that the partition 35 by being thus placed in the center of the box is adapted to separate coins dropped through the smaller slot 11 from those inserted 45 through the larger slot 12 which is offered as a decided improvement over the old method of leaving the coins in a jumbled mass.
- In operation my box is opened as follows: The curved covering 29 which corresponds to the ends 6 is slid to the rear on the molding 18 to assume the position shown in Fig. 2. The adjacent covering 29 is then slid outwardly from the molding 18 on the 50 front portion of the box and is entirely removed therefrom, this covering not being shown in Fig. 2. The locking lug 27 is thereby released and may be rotated upwardly and outwardly through an angle 55 of 90 degrees in order to release it from the cut out portion 28. When it is so released nothing remains but to pull the locking bolt 21 outwardly in the passage 20 until the keeper 23 has also been released 60 at which time the cover may be lifted and

access had to the contents of the receptacle. A reversal of these various processes of operation serve to lock the box securely and when the coverings 29 have been properly replaced upon their various moldings so 70 that their beveled ends 30 are in conjunction with each other, the box to all outward appearances is controlled only by the false lock 24. To further add to the ornamental 75 quality of the box and also to prevent the corners thereof from scratching or otherwise marring the highly polished surfaces of bureaus, dressers, etc., with which they might otherwise come in contact, it has been found desirous to provide the metal 80 knobs 36 which are rounded as shown in the drawing and serve to space the sharp edges of the box from the surface on which it rests.

While in the foregoing I have thus illustrated in the drawings and described in the specification such combination and arrangement of elements as constitute the preferred embodiment of my invention, I desire to emphasize the fact that I may make such 85 minor changes in the matters of proportion and degrees, in later adaptations of my device as shall not alter the spirit of my invention as defined in the appended claims.

What I claim is:

1. In a device of the character described, a box, end walls and side walls therefor, a cover hinged to one of said side walls, a false lock for said cover fixed on the other of said side walls, an ornamental molding 100 carried by said end walls and side walls, and actual locking means for said box hidden in said molding.

2. In a device of the character described, a box, end walls and side walls therefor, a cover hinged to one of said side walls, a false lock for said cover fixed on the other of said side walls, a molding carried by said end walls and side walls, and a covering 110 adapted to be slid longitudinally on said molding.

3. In a device of the character described, a box, end walls and side walls therefor, a cover hinged to one of said side walls, a false lock for said cover fixed on the other of said side walls, an apertured molding carried by said end walls and side walls, and actual locking means for said box slid- 115 able in said molding.

4. In a device of the character described, a box, end walls and side walls therefor, a cover hinged to one of said side walls, a false lock for said cover fixed on the other of said side walls an apertured molding carried by said end walls and side walls, and a covering 120 adapted to slide longitudinally on said molding.

5. In a device of the character described, a box, end walls and side walls therefor, a flanged cover hinged to one of said side 130

walls, false locking means carried by the other of said side walls to apparently coact with said cover a molding carried by said end walls, similar appearing but apertured 5 molding carried by said second side wall and actual locking means adapted to slide in said apertured molding.

6. In a device of the character described, a box, end walls and side walls therefor, a 10 flanged cover hinged to one of said side walls, false locking means carried by the other of said side walls to apparently coact with said cover a molding carried by said end walls, similar appearing but apertured 15 molding carried by said second side wall, actual locking means adapted to slide in said apertured molding, and curved coverings adapted to be longitudinally slid upon said molding to completely hide the 20 same.

7. In a device of the character described, a box, end walls and side walls therefor, a flanged cover hinged to one of said side walls, false locking means carried by the 25 other of said side walls to apparently coact with said cover, a molding carried by said end walls, a similar appearing but apertured molding carried by said second side wall and actual locking bolt slidable in said apertured 30 molding and a locking lug carried by said bolt at one extremity and adapted to coact with the unapertured molding of one of said end walls to securely hold said bolt.

8. In a device of the character described, a box, end walls and side walls therefor, a flanged cover hinged to one of said side walls, false locking means carried by the 35 other of said side walls to apparently coact with said cover, a molding carried by said end walls, similar appearing but apertured molding carried by said second side wall, an actual locking bolt slidable in said apertured molding and a locking lug carried by said bolt at one extremity and adapted to 40

coact with the unapertured molding of one 45 of said end walls to securely hold said bolt, and rounded coverings adapted to be longitudinally slid on both forms of said molding to completely hide the same.

9. In a device of the character described, a box, end walls and side walls therefor, a flanged cover pivoted to one of said side walls, false locking means carried by the other of said side walls, a pair of solid pieces of molding, one of which is carried 50 by each of said end walls, a pair of longitudinally apertured pieces of molding carried by second said side wall and spaced from each other, a locking bolt slidably positioned in said apertured molding and a keeper carried by said cover to apparently coact with said false locking means but in reality to coact with said locking bolt.

10. In a device of the character described, a box, end walls and side walls therefor, a flanged cover pivoted to one of said side walls, false locking means carried by the other of said side walls, a pair of solid pieces of molding, one of which is carried by each 65 of said end walls, a pair of longitudinally apertured pieces of molding carried by second said side wall and spaced from each other, a locking bolt slidably positioned in said apertured molding, a keeper carried by 70 said cover to apparently coact with said false locking means but in reality to coact with said locking bolt, and rounded covering pieces adapted to longitudinally slide on both forms, said molding to completely hide 75 the same.

In testimony whereof I have signed my name to this specification in the presence of two subscribing witnesses.

OSCAR ANDERSON.
